UNITED STATES PATENT OFFICE

94,185

DESIGN FOR A VELOCIPED

Giles E. Bullock, Rochester, N. Y., assignor to
E. C. Brown Co., Rochester, N. Y.

Application May 1, 1934, Serial No. 51,618

Term of patent 14 years

To all whom it may concern:

Be it known that I, Giles E. Bullock, a citizen of the United States, residing at Rochester, in the county of Monroe and State of New York, have invented a new, original, and ornamental Design for Velocipedes, of which the following is a specification, reference being had to the accompanying drawing, forming a part thereof.

Figure 1 is a view in side elevation of a velocipede showing my new design.

Figure 2 is a fragmentary top plan view thereof.

Figure 3 is a vertical sectional view of the step plate, taken on the line 3x-3x of Figure 2.

The dominant feature of the invention resides in the step plate shown in solid lines which has a substantially rectangular top plan view, a rearwardly tapering wedge shaped end view with a large semi-circular front edge and a small semi-circular rear edge so arranged that the top of the platform is substantially horizontal and the bottom edges of the sides thereof incline upwardly toward the rear thereof.

I claim:

The ornamental design for a velocipede as shown and described.

GILES E. BULLOCK.
